AUTOMATIC RECORD CHANGER FOR
PHONOGRAPHS

Benjamin L. Cartmell, Dayton, Ohio

Application July 27, 1935, Serial No. 33,552

19 Claims. (Cl. 274—10)

This invention relates to phonographs, and more particularly to mechanism for automatically interchanging records at the end of each playing period.

5 While the record changing mechanism, forming the subject matter hereof, is well adapted for home use, and is applicable to any disc type phonographic apparatus, the particular embodiment of the invention herein illustrated and described is especially designed for commercial use in amusement resorts, restaurants, and public places, and is therefore shown as equipped with an amplifier system and coin control means.

15 The present record changing mechanism is adapted to present multiple disc records in playing position by returning the previously played record to the top of a loose stack and removing the lowermost record of the stack for re-placement of such played record.

20 The control mechanism is so arranged that as the reproducer arm of the phonographic apparatus approaches the center of the record, at the completion of the playing operation, it closes a make and break contact in an electrical control circuit which causes a vertical stack of reserve disc records to be played to be automatically shifted from their normal position at one side of the phonograph playing table to a position over such table, and as the stack of records approaches the table, the previously played record is caused to be tilted upwardly into an inclined position. The stack of reserve records is then pushed beneath the upturned played record, which falls to flat position on top of the stack.

25 As the stack of reserve records approaches a position of registry with the phonograph playing table, a replacement record is dropped from the bottom of the stack on to the rotary table. The reproducer arm, which in the meantime has been returned to starting position by engagement therewith of a contact member moving with the stack of records, is then lowered on to the replacement record, as the stack of reserve records is returned to normal position in laterally offset relation with the phonograph table. The records are thus automatically interchanged and played in sequence.

30 In the event that it is desired to select a particular record from the stack other than the lowermost record thereof, the cycle of interchange operations can be repeated successively by manual operation of a selector button which closes the electrical circuit pertaining to the rec-

ord changing mechanism, until the desired record is deposited upon the rotary phonograph table. Otherwise the control circuit for the record changing mechanism is automatically closed by the action of the reproducer arm at the 5 conclusion of the record playing operation to effect an automatic exchange of the played record for the next record of the series. The actuation of the record changing mechanism, whether effected automatically by the reproducer arm 10 or manually by operation of a selector circuit button, does not set the phonograph table in operation to play the positioned record. The playing of the selected record is initiated by subsequent depression of a plunger button which effects closure of the phonograph motor energizing circuit, unless in a coin controlled apparatus 15 a number of reserve coins have been deposited, in which event the interchange and playing of records will be automatically repeated until the 20 coin supply is exhausted.

35 For commercial operation, the control circuits are so arranged that it is necessary to deposit a proper coin before the record changer actuating circuit can be closed by the selector button. 25 However, if no selection of records is to be effected, but the record which has been previously automatically positioned is to be played, the playing button or plunger may be operated to set the apparatus in operation without manipulation of the selector. Upon depression of the 30 playing plunger, the same coin which may have enabled the repeated operation of the record changing mechanism any number of times to bring the desired record on to the playing table 35 is also effective to close the phonograph motor circuit. At the time the phonograph motor circuit is closed to play the record, the record changer control circuit is automatically opened to prevent the record changer being set in operation before the playing operation has been 40 completed. Provision is made, however, for deposit of a reserve supply of coins which will cause the cycle of record changing and playing operations to be automatically repeated until 45 the coin supply is exhausted. The supply of deposited coins may be held in reserve for either record selection operation and utilized one at a time for playing the records as selected, or for automatic repetition of the playing operations 50 in which case the records are interchanged and played in sequence.

55 The object of the invention is to improve the construction as well as the means and mode of operation of phonographic record changing ap-

paratus, whereby such apparatus may not only be cheapened in construction, but will be more efficient in use, of compact form, automatic in action, and unlikely to get out of order.

5 A primary object of the invention is to provide a new method of interchanging records and a new sequence of operation for effecting automatic interchange thereof.

10 A further object of the invention is to provide an improved method of selecting records to be played, and to provide an improved method of controlling the interchange of records.

15 A further object of the invention is to provide a record changing apparatus wherein the record discs are loosely stacked and successive records automatically removed from the stack and returned thereto.

20 A further object of the invention is to provide improved means for controlling the operation of the record changing mechanism by the action of the phonographic pickup arm or reproducer.

25 A further object of the invention is to provide selective means for presenting in playing position at will any particular record of a series without playing the records consecutively.

30 A further object of the invention is to provide means for automatically preventing actuation of the record changing mechanism while the playing of a selected record is in progress.

35 A further object of the invention is to provide improved means for controlling the pickup or reproducer arm of the phonograph by the actuation of the record changing mechanism.

40 A further object of the invention is to provide improved means for returning the reproducer arm to its starting position at the completion of a playing period, and for repositioning the reproducer upon a replacement record preparatory to the next playing operation.

45 A further object of the invention is to provide an improved mechanism for enabling a predetermined number of records to be automatically interchanged and played in consecutive order.

50 A further object of the invention is to enable the interchange and playing of records to be automatically arrested when a predetermined number of records have been consecutively played.

55 A further object of the invention is to provide coin control means wherein multiple deposited coins may be consecutively utilized one at a time for selective record changing operation.

60 A further object of the invention is to provide coin control means wherein multiple deposited coins may be consecutively utilized one at a time for successive record playing operations.

65 With the above primary and other incidental objects in view, as will more fully appear in the specification, the invention consists of the features of construction, the parts and combinations thereof, and the mode of operation, or their equivalents, as hereinafter described and set forth in the claims.

70 Referring to the accompanying drawings, wherein is shown the preferred but obviously not necessarily the only form of embodiment of the invention:

Fig. 1 is a top plan view.

Fig. 2 is a side elevation, viewed from the upper side of Fig. 1.

Fig. 4 is a similar transverse sectional view on the same line viewed toward the left.

Fig. 5 is a transverse sectional view on line 5—5 of Fig. 1, viewed toward the right.

Figs. 6, 7, 8 and 9 are all longitudinal sectional views on line 6—6 of Fig. 1, the respective views showing the record changing apparatus in successive positions of adjustment.

Fig. 10 is a perspective detail view of the coin control mechanism. 5

Fig. 11 is a detail view of the playing plunger or button for initiating the playing operation.

Fig. 12 is a detail view of the playing key and associated parts. 10

Fig. 13 is a diagrammatic view of the electrical control circuits.

Fig. 14 is a perspective view of the cabinet in which the phonograph apparatus and record changing mechanism is housed. 15

Fig. 15 is a perspective view of the switch mechanism for instituting operation of the record change mechanism.

Like parts are indicated by similar characters of reference throughout the several views. 20

For convenience and accessibility, the various operating parts of the apparatus are mounted upon a double deck chassis which is bodily removable from the cabinet 1. Upon the upper deck 2 of the chassis there is mounted the rotary phonograph turn table 3 actuated by the usual driving motor 4 suspended beneath the chassis deck 2, and adjustably mounted adjacent to the turn table is the usual pickup arm or tone arm 5 provided at its free end with the usual pickup head 6 carrying the tracer needle or stylus which engages in the customary manner the record grooves in the face of the record discs upon the turn table 3. 25

Also mounted upon the upper deck 2 of the chassis and normally at one side of the turn table 3 is a reciprocatory record disc magazine movable within parallel spaced guide or track rails 7 into and out of overlying relation with the turn table 3. The record magazine or carriage comprises a rectangular frame 8 including parallel side bars 8a, interconnected by transverse end bars 8b, and supported upon rollers 9 for to and fro travel movement upon the chassis deck 2 within the guide or track rail 7. At its forward end the magazine or record carrier is provided with spaced ledges or supporting lips 10 separated by an intervening space 11 coincident with a shallow notch 12 in the lower margin of the forward transverse frame bar 8b, of the carrier. At its rear end the magazine or carrier is provided with an inwardly extending medial lip or ledge 13, above which is positioned a stop or abutment 14, the lower margin of which is spaced above the supporting lip or ledge 13 a distance substantially equal to or slightly greater than the thickness of one record disc, but less than that of two discs. 45

50 A considerable number of reserve record discs stacked one upon another may be supported upon the inwardly projecting ledges 10 and 13 at the forward and rearward sides of the magazine or carriage 8. 55

55 Stationarily located upon the upper deck 2 of the chassis in parallel spaced relation between the side members of the traveling magazine or record carriage, is a pair of supporting rails 15 carried in elevated position upon posts 16 and serving to medially support the records in the event that there is any tendency of the records to sag or buckle. The elevated supporting rails 15 are stationary and the traveling magazine or record carriage moves relative thereto, carrying the record discs over such rails. The record discs do not ordinarily contact nor slide upon the rails 15, but normally clear such rails which are safety devices to support the lowermost disc in the event 70

75

that it is accidentally dislodged from the magazine or carrier when the latter is in its retracted position, and also to support the discs in the event they are distorted or misshaped.

5 Transversely disposed in elevated relation above the traveling magazine or carriage is a bridging bar 17, carrying at a medial position thereon an adjustable contact plate 18 for engagement with the head 6 of the pickup arm for returning the 10 arm to its starting position at each operation of the magazine carriage, as will be hereafter described.

15 The reciprocatory magazine carriage is actuated to and fro in a properly timed cycle of operation by means of an actuating lever 20 pivoted at 21 to a suitable bracket upon the lower deck of the chassis, the free end of which is connected by a link 22 with a dependent arm 23 projecting from the traveling magazine carriage beneath the rear disc supporting ledge 13.

20 The actuating lever 20 is connected by a pitman or connecting rod 24 with a crank arm 25 driven by an electric motor 26 through a suitable speed reduction unit 26a. The motor energizing circuit is controlled, as hereafter described, to 25 arrest the motor 26 when the crank arm 25 has made one complete rotation to thereby shift the magazine carriage 8 from its normal position at one side of the phonograph turn table 3 to a position over such table and then back to its normal 30 position. During this to and fro motion of the magazine carriage, the pickup arm is raised off the played record and by engagement of the contact plate 18 therewith is oscillated laterally to its starting position and the played record is tilted 35 to an inclined position permitting the magazine carriage and the reserve supply of discs to enter therebeneath, and at the limit of the travel of the magazine carriage the lowermost disc record is deposited therefrom on to the turn table 3.

40 To enable the return of the pickup arm 5, the supporting post 27 upon which the arm 5 is mounted for to and fro horizontal swinging motion, is in turn carried upon a rock shaft 28 disposed horizontally above the upper deck 2 of the 45 chassis in suitable bearing brackets 29. The rock shaft 28 carries at its end opposite the pickup arm supporting post 27 a horizontally projecting rock arm 30 provided at its extremity with a roller 31 aligned with a cam bar 32 fixedly secured to one 50 of the side bars 8a of the reciprocatory magazine carriage. In the initial advance movement of the magazine carriage, the tapered forward end of the cam bar 32, engaging beneath the roller 31, lifts the rock arm 30 to oscillate the rock shaft 28, thereby tilting the supporting post 27 of the pickup arm 5 to lift the arm 5 and pickup head to elevated position above the played record upon the turn table 3.

To facilitate this elevation of the pickup arm 60 and minimize the load upon the traveling carriage, the rock arm 30 is connected by a retractile spring 33 with an overhanging standard 34 which, while insufficient to overcome the weight of the pickup arm, nevertheless augments the lifting action 65 of the cam bar 32 as the magazine carriage advances.

During the advance of the magazine carriage by which the pickup arm is elevated from the position shown in Fig. 6, wherein the parts are 70 illustrated in their normal or record playing relation, to that disclosed in Fig. 7, wherein the movement of the record carriage has been initiated and the pickup arm elevated, the played record A has also been lifted from the phonograph table 3 into a tilted or inclined position.

The elevation of the played record from the table 3 is effected by lifting arms 35 pivoted at 36 to the upper deck of the chassis in the path of travel of the reciprocatory magazine carriage and extending into proximity with the periphery of the 5 phonograph table 3 at opposite sides thereof.

10 The lifting arms 35 are provided adjacent to their supporting brackets 36 with vertical inclined deflections or bends 37, and adjacent to their free ends they are formed with additional lateral deflections or offsets 38. At their extreme ends they are provided with pads 39 of rubber or other suitable cushion material for contact engagement with the under side of the played record A as these lifting arms are oscillated upwardly about their 15 pivotal connection with their brackets 36.

For oscillating the lifting arms in properly timed relation with the movement of the reciprocatory magazine carriage, there are provided 20 spring arms 40 attached to the inner sides of the side bars 8a of the magazine carriage and extending parallel therewith in inwardly spaced relation. At the ends of such spring arms 40 there are carried rollers 41 normally positioned beneath the lifting arms 35 adjacent to their pivotal connection 25 with their brackets 36. As the magazine carriage advances, the rollers 41, upon the spring arms 40, engaging the inclined deflection or bends 37 of the lifting arm 35, exert camming action thereon to lift the arms upwardly causing the padded extremities 39 to engage the played disc and lift it from the table 3 into inclined position as shown in Fig. 7.

As the magazine carriage continues to advance, it enters beneath the tilted record, as shown in 35 Fig. 8, and the rollers 41 advancing with the carriage pass beyond the lateral deflections 38 of the lifting arms 35 whereupon these lifting arms may drop to their normal position upon the deck of the chassis as shown in Fig. 8.

40 As the point of engagement of the reciprocatory magazine carriage passes beyond the center of the disc, the latter will tilt by gravity into a horizontal position on top of the stack of reserve discs carried by the magazine carriage and will abut 45 against the post 42 located beyond the limit of the range of travel of the magazine carriage and having a cushion head 43, preferably of rubber, which holds the elevated disc against travel movement while the magazine carriage and the 50 stack of records therein continue to advance beneath the elevated record A.

At the limit of travel of the carriage the record has been positioned upon the top of the stack concentric with the reserve records. However, 55 during the final approach of the magazine carriage to the limit of its range of travel, the forward transverse bar 8b thereof has passed slightly beyond a stationary pin 44 located in front of the abutment post 42 which, entering through 60 the notch 12 in the bottom of the carriage bar and through the space 11 between the supporting ledges 10 thereof, will have caused the lowermost record disc of the stack to be arrested slightly 65 before the carriage reaches the limit of its travel and thereby pushed rearwardly relative to the carriage off the forward supporting ledges 10 and within the space beneath the rear abutment member 14, thereby allowing the disc to drop on to the turn table 3 in a slightly inclined position, as 70 shown in Fig. 9, in which the center pin 45 of the turn table engages the central hole of the disc thereby preventing retractive movement of the disc with the return of the carriage.

As the carriage begins its return movement, 75

the lowermost disc being held by the central stud or pin 45 of the turn table will be withdrawn from the rearmost supporting ledge 13 of the magazine carriage and thereupon falls into playing position upon the phonograph turn table 3. The pickup arm 5, held in elevated position by the engagement of the cam bar 32 beneath the roller 31 of the rack arm 30, having been swung laterally to its starting position by the 10 contact of the plate 18 upon the transverse bridge bar 17 rests against a spring arm 46 located adjacent to the abutment post 42. This spring arm 46 is preferably deflected or curved at its upper extremity whereby, as the pickup head 6 later 15 descends, the arm will exert a slightly tensioned camming action inwardly relative to the record to properly position the stylus of the pickup head at the beginning of the playing groove of the record.

20 The magazine carriage continuing its rearward or retractive movement, leaves the deposited record upon the turn table and returns to its normal position, illustrated in Fig. 6. As the magazine carriage approaches the limit of its 25 range of retractive travel the roller 31 of the rock arm 30 passing down the inclined end of the cam bar 32 gradually lowers the pickup arm 5 until the stylus is in engagement with the newly deposited record. In its descent on to the record, 30 the pickup head 6 is cammed slightly inwardly by the spring arm 46 which is tensioned somewhat by contact of the pickup head therewith to shift the head across the smooth margin of the disc until the stylus engages the initial record 35 groove. At the limit of the return movement, the energizing circuit of the motor 26 is opened and the carriage comes to rest.

While the reproduction, in the present instance, is effected electrically and amplified 40 through a conventional vacuum tube amplifier unit 47 connected with a typical speaker unit 48, it is to be understood that such method of electrical reproduction is not essential but the arm 5 and head 6 may be a conventional tone arm and diaphragm type reproducer well known 45 in the phonographic art.

Electrical control.—The traveling magazine carriage is set in operation automatically to interchange the records at the end of each playing 50 operation by the closing of the energizing circuit pertaining to the motor 26. This circuit, however, may be manually closed and the motor energized to effect repetition of the record exchange in order that any desired record of the 55 reserve supply may be positioned for playing.

At the present time most commercial phonograph records are provided centrally with either an eccentric or involute continuation of the record grooves of exaggerated pitch by which the 60 pickup or tone arm, as the case may be, is given a continued oscillatory movement after the completion of the record playing period. Such continuation of the stylus track upon the record is for the purpose of operating the record changing 65 mechanism, for which purpose it is also utilized in the present instance.

For automatically setting in operation the record exchange apparatus there is provided adjacent to the pickup arm supporting post 27 an 70 electrical circuit closer comprising two independently pivoted contact blades 50 and 51 mounted upon a suitable block 52 of insulation material. The contact blade 50, which is pivoted at 53, carries an upstanding spring fork or bifurcated 75 gripping arm 54, through which extends a fric-

tion rod 55 connected with a rock arm 56 projecting from the pickup arm post 27. To increase the tenacity of the friction rod 55, that portion thereof engageable within the spring fork or gripping arm 54 of the contact blade 50 is 10 preferably, although not necessarily, rubber covered. As the pickup arm 5 travels inwardly toward the center of the record being played, the supporting post 27 rotating with the arm exerts a pulling influence through the rock arm 56 upon the friction rod 55 to draw the rod through the spring fork or gripper arm 54 against the tension thereof, thereby tending to move the contact arm 50 about its pivotal connection 53 downwardly and away from the second contact blade 15 51 thereby maintaining the electrical contact between such members open.

However, when the playing stylus, carried by the pickup head 6, passes beyond the record grooves of the disc and into the eccentric or 20 other irregular continuation thereof by which a slight to and fro motion is transmitted to the pickup arm, the incidental reverse movement of the pickup arm will be transmitted through the rock arm 56 to exert a pushing influence upon the friction rod 55 which will tend to turn the gripping arm 54 and with it the contact blade 50 about their pivotal connection 53, causing the blade 50 to make contact with the blade 51 and thereby close the actuating motor circuit. 30

Phonographic records of certain manufacturers are not provided with continuing eccentric grooves necessary to produce the reversal of the pickup arm movement necessary to elevate the contact blade 50 and close the motor control circuit, therefore, to make the apparatus universal and enable the control circuit to be closed to effect interchange of records regardless of the type of record being played, the circuit closer blade 51 is provided with an upstanding portion 40 58 projecting into the path of a dependent vane or contact portion 59 carried upon the friction actuating rod 55. This contact vane 59 is adjustable longitudinally of the actuating rod 55 by adjustment of the nuts 60, screw threaded thereon at opposite sides of the contact vane. As the playing stylus reaches the end of the record groove in the disc record the contact vane 59 will engage the upstanding portion 58 and by continued movement of the pickup arm and the 50 rod 55 the contact blade 51 will be depressed against the yielding resistance of an L-shaped elevating spring 61 secured to the mounting block 52 at the side opposite the contact blades 50 and 51 and having its lateral arm extending transversely of the end of the mounting block 52 and beneath the contact blade 51. 55

Thus at the limit of the playing period of one type of disc record the continuing eccentric record grooves by causing a limited to and fro movement of the pickup arm 5 will cause the contact blade 50 to be elevated into closing engagement with the contact blade 51 by pushing effort of the friction rod 55 against the bifurcated gripping arm 54. When the record disc is of different type 60 wherein no limited reversal movement of the pickup arm is effected, the continued inner movement of the pickup arm will cause the contact blade 51 to be depressed against the tension of the spring 61 into engagement with the contact blade 70 50 by the continued pulling effort upon the operator rod 55 which is transmitted to the contact vane 59 and projecting portion 58 to the circuit closing blade 51.

As is illustrated in the circuit diagram, Fig. 13, 75

the operating current is supplied from the power line 62 for the various electrical operations, the voltage of which is reduced through the transformer 64 to a shunt circuit in which is included 5 the automatic switch heretofore described. As shown in the circuit diagram, one contact blade of the circuit closer 50-51 is connected through the line 63 with one output terminal of the transformer 64. The other contact blade of such circuit closer is connected through the line 65 with 10 electro-magnet coils 66 which are in turn connected through the line 67 with the opposite terminal of the transformer. The closing of this circuit energizes the electro-magnet 66 to attract 15 its armature 68, best illustrated in Fig. 2. The armature bar 68 is pivoted at its lower end to the free end of a lever 69 which is pivoted at 70 and capable of limited oscillatory movement against the tension of a retracting spring 71. 20 The armature bar 68 normally supports in an elevated position a circuit closer arm 72 which normally rests upon a stud or pin 73 projecting from the armature bar 68. The armature bar 68 is provided with a retracting spring 74, against 25 the tension of which the armature bar is retracted by the energization of the electro-magnet 66 to withdraw the supporting pin 73 from beneath the circuit closing arm 72 allowing the arm 72 to drop by gravity into closing contact with 30 a stationary terminal 75. The closing of the contacts 72 and 75 closes the motor energizing circuit through the line 76 from the transformer 64 to the circuit closing arm 72 and thence from the contact 75 through the line 77 to the actuating 35 motor 26, the opposite side of which is connected through the line 78 to the opposite terminal of the transformer 64.

The motor circuit being thus closed, the motor 40 is energized to actuate the parts through one complete rotation of the driving crank arm 25 which is connected through the link 24 and arm 20 with the magazine carriage to effect one complete advance and return movement of the latter, during which the previously played record is removed from the table 3 and the succeeding lower-most record is deposited thereon.

As the driving crank 25 completes its rotary motion, a contact finger 79, carried by the motor shaft and rotating in unison with the crank arm 50 25, contacts a cam surface 80 upon the lower side of the pivoted lever 69 beyond its pivotal point 70. This engagement of the contact finger 79 with the cam surface 80 oscillates the lever 69 against the tension of its retracting spring 71 to 55 draw the armature bar 68 downwardly until the pin 73 then resting against the end of the circuit closing arm 72 may pass beneath such arm under influence of the retractile spring 74 connected to the armature bar 68. As the contact finger 60 79 passes beyond the cam surface 80, the spring 71, returning the oscillated arm 69 and the armature bar 68 upwardly, will cause the circuit closing arm 72 to be lifted by the pin 73 from its closing engagement with the contact terminal 75, thereby 65 again opening the motor energizing circuit and the parts will come to rest at the completion of one cycle of record changing operation with the magazine carriage in its normal retracted position as shown in Figs. 1, 2 and 6.

70 By the means thus described the control circuit is closed at the end of the playing operation to energize the electro-magnet 66, which in turn effects the closing of the motor energizing circuit to set in operation the motor 26 to actuate the 75 record changing apparatus through one cycle of

operation, thereby automatically changing the next record of the series for the previously played record.

It may be desired, however, to play some particular record of the reserve supply other than 5 the next of the series. Means is therefore provided for effecting repetition of the record exchange operation until the desired record disc is deposited upon the rotary phonograph table 3. To this end there is provided a manually operated 10 depressible circuit closing button 82 connected at one side with the line 65 leading to the electro-magnet coils 66 and then through the line 67 to one side of the transformer and connected at its opposite side through a line 83, which in turn 15 connects through included circuit closing elements with the line 78 communicating with the opposite terminal of the transformer 64.

Thus when the button 82 is depressed and the circuit closed through the coils 66, the armature 20 bar 68 will be attracted to release the circuit closing arm 72 which, by its descent into engagement with the terminal 75, closes the circuit through the actuating motor 26 to operate the record exchange apparatus as before described. 25 This manually operated button 82 may be depressed any number of times to repeat the record exchange operation until the desired record has been selected and deposited upon the rotary table 3. 30

The desired record, having been selected and deposited, the turn table actuating motor 4 is then set in operation by closing an additional circuit closer 85 included in a motor energizing circuit comprising the lines 86, 87 and 88 by 35 which the turn table motor 4 is bridged across the power line 62. At the completion of the playing period, the circuit closer 85 is opened automatically to deenergize the turn table motor 4 by the movement of the magazine carriage actuating arm 20. This is effected by a rock shaft 89 journaled in spaced upright supports 90 and 91 and having at its extremity an extended rock arm 92, extending into the path of a stud or roller 40 93 carried by the arm 20 by which the magazine carriage is reciprocated. 45

The rock shaft 89 also carries a short rock arm 94 to which is pivoted a pawl 95 engageable with a vertically moving rack bar 96. In the drawings, the rack bar 96 has been illustrated as 50 provided with a series of spaced studs or pins 97 projecting perpendicular to the plane of the bar 96 with which the pawl 95 engages. The pawl 95 is pivoted to the arm 94 for idle oscillation in one direction. 55

As the elongated rock arm 92 is elevated by the action of the magazine carriage operating arm 20, the short rock arm 94 is depressed, causing the pawl 95 to move idly over one of the pins or teeth 97 of the rack bar against the yielding resistance of a retracting spring 98 which tends to return the rock shaft 89 and the arms 92 and 94. 60

As the magazine carriage operating arm 20 returns to normal position at the completion of the record changing operation, it permits the 65 elongated rock arm 92 and with it the shaft 89 to likewise return to normal under influence of the retracting spring 98. However, during this return movement the pawl 95 will have engaged beneath one of the projecting pins or teeth 97 of the reciprocatory rack bar 96, and the return movement of the shaft 89 and arm 94 will serve to elevate the rack bar 96 a distance of one step. This reciprocatory rack bar 96, slidingly mounted in suitable ways 99, has operative connection with 70 75

the circuit closer 85 pertaining to the phonograph motor circuit. Pivotedly connected to the circuit closer arm 85 is a vertically moving bar 100, from which projects upward a rod or stem 101, the upper end of which is bent laterally to form a hook or offset which overhangs a pin 102 projecting from the lower end of the reciprocatory rack bar 96. As the rack bar 96 approaches the upper limit of its range of travel under influence of the elevating pawl 95, the pin 102 engaging beneath the offset upper end or hook of the stem 101 draws the circuit closer arm 85 upwardly thereby opening the motor circuit and arresting the rotation of the table 3.

15 The vertically moving bar 100, connected to the circuit breaker arm 85, also controls a circuit closer in the selector control circuit line 83. This circuit make and break device comprises a pivoted contact arm 103, one extremity of which 20 extends within the path of the vertically moving bar 100 and is engaged thereby to open the selector control circuit line 83 when the playing circuit is closed by the descent of the circuit closing arm 85. To the contrary, the opening of 25 the playing switch 85 by the elevation of the rack bar 96 upon completion of the cycle of operation, as before described, will allow the circuit closer 103 to automatically close the selector circuit. Thus the circuit closer 85 in the phonograph motor circuit and the circuit closer 103 in the selector button circuit, controlled by the button 82 operate alternately, that is, when one of these circuit closers is open the other is closed and vice versa. By this means it is impossible to 30 operate the selector button 82 to set in operation the record changing apparatus until the playing of the record has been completed and the record changing apparatus control circuit has been automatically closed by the movement of the pickup arm 5, and conversely the operation of the circuit closer 85 to set in operation the phonograph turn table automatically opens the contact 103 and renders the manual selector button 82 ineffective.

45 The opening and closing of the phonograph motor circuit, and incidental thereto the opening and closing of the manual selector circuit, is controlled entirely by the vertical adjustment of the rack bar 96 which, as before described, engages 50 at its upper limit of range of travel with the stem 101 to lift the contact 85 and bar 100.

The rack bar 96 descends within its ways 99 by gravity and such descent is controlled by an oscillatory escapement pallet 105 which is pivoted at 106 and subject to retractive influence of a spring 107. The escapement device is provided with two spaced teeth 108 engageable alternately with the teeth or studs 97 of the vertically moving rack bar 96, and also is provided with an 60 operating arm 109 terminating in a slightly curved plate 110.

As the arm 109 and plate 110 are depressed against the retractive influence of the spring 107, one of the detent teeth 108 is projected into the path of a pin 97 of the rack bar 96 slightly before the other tooth 108 is withdrawn from engagement with a different tooth or pin thereof, thereby allowing the rack bar 96 to drop a limited distance until arrested by the escapement device. 65 At each oscillation of the escapement device 105 the rack bar will be allowed to drop the distance of one predetermined step as defined by the space between succeeding studs or teeth 97. Thus by operating the escapement device several times 70 in succession and allowing the rack bar to de-

scend a like number of steps or spaces, the playing control switch 85 will not be opened until the rack bar has been again elevated through a like number of steps or spaces whereby the extended pin 102 will again engage and elevate the stem 101 to again open the contact 85. Inasmuch as the rack bar 96 is elevated only one step or space at each operation of the rock shaft 89 and pawl arm 94, it necessarily follows that the cycle of operation of playing and interchanging records 10 will be repeated as many times as the rack bar has been permitted to descend through succeeding steps or spaces and in turn this corresponds to the number of times the escapement device 105 has been actuated. 15

The escapement device is operated by means of a depressible playing key or plunger 111 having on its inner end a cam portion 112 engageable with the curved plate 110 of the escapement arm 109 to depress the arm and operate the escapement to permit the descent of the rack bar 96 one step or space at each operation of the playing key or plunger 111. Each time the playing key or plunger 111 is depressed, the rack bar 96 is allowed to descend one space or step. Consequently if the playing key or plunger 111 is depressed but once the apparatus will be set in operation and upon the completion of the playing of the record then upon the turntable 3, the record changing apparatus will be operated through a complete cycle to exchange the record, replacing it with the next record of the series, and the apparatus will come to rest with the circuit closer 85 of the phonograph motor 4 elevated by the return of the rack bar 96 to its 35 uppermost position by the action of the pawl 95.

However, if the playing key or plunger 111 is depressed a number of times in succession, the escapement 105 being operated at each depression to permit the descent of the rack bar an 40 additional step or space from which it is returned one step or space at each actuation of the elevating pawl 95, the apparatus will operate through succeeding cycles without stop until the rack bar has been elevated through a like 45 number of steps and returned to the uppermost position wherein it operates to lift the contact 85 by engagement of the pin 103 with the stem 101.

Thus before the playing key or plunger 111 is depressed, the operator may depress the selector button 82 any number of times until a desired record is deposited upon the turn table 3, but the record will not be played until the playing key or plunger 111 is depressed. However, 55 the playing key or plunger may be depressed any number of times to effect automatic repetition of the cycle of operation by which succeeding records are deposited upon the turn table 3 played and removed therefrom, and until such 60 sequence of records has been completed, the selector button 82 remains ineffective due to the fact that the circuit closer 103 is maintained open so long as the contact 85 is closed.

The construction and operation as heretofore described is that for home use or for uncontrolled and unrestricted interexchange and playing of records.

For use, however, in public places the construction illustrated and as heretofore described is 70 easily and conveniently adapted for commercial exploitation through coin control operation. In lieu of depressing the escapement arm 109 by the camming action of the playing key or plunger 111, the escapement may be operated by the 75

5 weight of a dropping coin, but before the coin is released for impingement upon the escapement operating plate 110, it is temporarily arrested by a pair of spaced contacts in the line 83
5 of the selector circuit to temporarily close the selector circuit so that the button 82 may be operated any desired number of times to select a particular record to be played, the presence of the coin being necessary to close this circuit.
10 After the selection has been made, the coin is dislodged from the spaced selector circuit terminals by depression of a playing key or plunger and is caused to fall upon the escapement operating plate 110 whereupon the operation is as
15 before described.

Such coin control system is illustrated in Figs. 10 and 11 wherein 113 is a coin chute leading downwardly in a somewhat inclined direction from the exterior of the cabinet 1. Projecting 20 into the path of the coin as it passes from the lower end of the inclined coin chute 113 are two spaced electrical terminals 114 connected into the line 83 of the selector circuit, as shown in Fig. 13, which intercepts the descending coin 25 and upon which the coin temporarily lodges. The engagement of the coin 115 with the spaced electrical terminals 114 closes the selector circuit therebetween and renders the selector button 82 effective for repeated operation of the record 30 changing apparatus so long as the coin 115 remains in bridging relation with the terminal stud 114.

35 A hook-shaped spring finger 116, secured to the rear side of the coin chute and terminal support 117, extends about the margin of the support 117 and overhangs the deposited coin 115 to prevent it from bouncing off the contact 114 or being accidentally dislodged therefrom.

Behind the coin position 115, the spring finger 40 116 is provided with a stud 118 projecting through a corresponding hole in the support 117 and adapted upon deflection of the hook-shaped spring finger 116 to dislodge the coin 115 from the supporting terminals 114 across which it is 45 bridged.

50 A playing key or plunger 119a projecting from the front of the cabinet 1 is adapted upon depression to flex the spring finger 116 sufficiently to cause the stud 118 carried thereby to push the coin off the supporting electrical terminals 114. The dislodged coin then falls through a bottomless guide chute 119, beneath which the operator plate 110 of the escapement device extends. The coin 115, dislodged from the selector circuit terminals 114 falling through the guide chute 119, 55 impinges upon the plate 110 with sufficient force to depress the escapement device 105 against the tension of its retracting spring 107 and thereby releases the rack bar 96 for descent through one 60 step or space.

If only a single coin is deposited in this manner, the apparatus will be operated through but a single cycle of operation and will come to rest when one record has been played and another has 65 been substituted therefor preparatory to the next playing operation. However, any number of coins may be deposited in succession without waiting for the completion of any playing period. The deposit of each coin will operate the escapement to permit descent of the rack bar 96 through 70 one additional step or space and thereafter the cycle of operation will be repeated as many times as there have been coins deposited.

The coin chute 113 which extends to the exterior of the cabinet 1 to receive the deposited

coins is sufficiently long that a number of coins may be retained therein, the lowermost of which will rest on and bridge the terminals 114 thereby enabling the changing apparatus motor circuit to be closed by depression of the button 82. The remainder of the deposited coin supply will be supported on the lowermost coin. As the plunger 119a is depressed the lowermost coin will be dislodged from the contacts 114 and fall onto the escapement pallet 112 to actuate the control bar 10 escapement, and the next succeeding coin in the chute 113 will take its place bridging the terminals 114. Thus a reserve supply of coins may be deposited in the chute and used each in turn to enable repetitious operation of the record changing apparatus to select particular records out of their sequential arrangement in the magazine carriage. In lieu of holding the supply of coins in reserve for record selecting purposes, a series of coins may be consecutively deposited through the 20 chute into the apparatus by repeated operation of the playing plunger 119a, even while the apparatus is in operation. Each coin falling on the pallet 112 will operate the escapement 105 to advance the control member 96 one step. The 25 rack bar 96 may thus be advanced a succession of steps by deposit of a like number of coins, thereby causing continuous repetition of the playing operation and record changing operation until the rack bar has been retracted a like number 30 of steps, by the pawl 95, which operates the rack bar one step, once for each record changed, until the control bar is returned to normal. However when the control bar 96 is fully retracted and the button 82 is depressed to select a record the 35 retracting means 92-94 and 95 will operate idly. From the above description it will be apparent that there is thus provided a device of the character described possessing the particular features of advantage before enumerated as desirable, but 40 which obviously is susceptible of modification in its form, proportions, detail construction and arrangement of parts without departing from the principle involved or sacrificing any of its advantages.

45 While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the 50 appended claims.

Having thus described my invention, I claim:

1. A phonographic apparatus including a record disc receiving turn table and a swinging pick-up arm cooperating with a disc record thereon, 60 characterized by a magazine carriage for a supply stack of superposed record discs movable to and fro into and out of registry with the turn table, said magazine having an open bottom through which discs are dropped vertically on the 65 turn table when in registry therewith, elevating means operable in timed relation with the movement of the magazine carriage for lifting a record from the table in advance of the engagement of the carriage and the parts associated therewith 70 with the record, a distance sufficient to permit the carriage and supply of discs carried thereby to enter beneath the elevated record disc, a contact portion upon the traveling carriage engageable with the pick-up arm for returning the arm to 75

starting relation, and means engaged by the lowermost disc of the supply stack as the carriage approaches the limit of its advanced movement for dislodging the lowermost disc of the supply stack from the carriage preparatory to deposit thereof onto the turn table.

2. In an apparatus wherein successive phonographic record discs are to be deposited upon and removed from a phonographic turn table whereon they are operatively engaged by a phonographic pick-up arm, a traveling magazine carriage for a stack of superposed record discs movable to and fro into and out of overlying relation with the phonographic turn table, elevator means operable by advance movement of the traveling magazine into overlying relation with the turntable for raising a previously deposited record from the turntable, fore and aft supporting ledges on the carriage engaged by the lowermost disc of the supply stack for removably supporting the superposed record discs thereon, the rearward ledge being of greater length than the forward ledge, stop means engaged by the lowermost disc of the stack before the carriage reaches the limit of its forward travel for arresting the lowermost record disc substantially in registry with the phonographic turn table while the continued advance of the carriage withdraws the forward supporting ledge from thereunder permitting the lowermost disc to descend onto the turn table, the rear supporting ledge being withdrawn from under the lowermost record upon return movement of the carriage leaving the record in playing position upon the turn table.

3. In an apparatus wherein successive phonographic record discs are to be deposited upon and removed from a phonographic turn table whereon they are operatively engaged by a phonographic pick-up arm, a traveling magazine carriage for a stack of superposed record discs, means for advancing the carriage into and out of overhanging relation with the turn table, a discharge outlet in the bottom of the magazine through which record discs are successively dropped vertically onto the turn table when in registry therewith, means for releasing the record discs one by one from the bottom of the stack onto the turn table when in such overlying position, elevator means operable by the advance movement of the carriage for raising a previously deposited record from the turn table into an inclined position prior to the engagement therewith of the carriage and associated parts traveling with the carriage to permit the carriage and supply stack of records to advance thereunder whereby the record thus removed from the turn table will be received on top of the supply stack.

4. In an apparatus wherein successive phonographic record discs are to be deposited upon and removed from a phonographic turn table whereon they are operatively engaged by a phonographic pick-up arm, a mounting for said arm upon which the pick-up arm is mounted for both vertically swinging and horizontally swinging motion, a traveling magazine carriage for a supply stack of superposed record discs movable into and out of overlying relation with the turn table, record elevating means operable to lift a record to an inclined position on the turn table in advance of the engagement therewith of the traveling carriage and associated parts traveling with the carriage for replacement upon the top of the supply stack, record releasing means operable before the carriage reaches the limit of its forward travel to dislodge the lowermost record of

the stack preparatory to deposit thereof upon the turn table when the magazine carriage is in overlying relation with the turn table, and means operated by the travel of the carriage for initially elevating the pick-up arm through its vertical swinging movement and by further travel motion thereof shift the elevated pick-up arm through its horizontal movement to starting position.

5. In an apparatus wherein successive phonographic record discs are to be deposited upon and removed from a phonographic turn table whereon they are operatively engaged by a phonographic pick-up arm, a traveling magazine carriage for a supply stack of superposed record discs movable to and fro into and out of overlying relation with the turn table, tilting means operated in unison with the travel of the carriage for elevating one edge of a record disc from the turn table to inclined position thereabove in advance of its engagement by the carriage or associated traveling parts whereby the carriage and stack of records carried thereby may enter therebeneath, disc releasing means for dislodging the lowermost record disc of the stack by the continuing advance movement of the carriage when positioned over the table, means for initially elevating and subsequently shifting the pick-up arm from finish to starting position in unison with the movement of the carriage, and actuating means for the apparatus.

6. A phonographic apparatus wherein a swinging pick-up arm coacts with a record disc upon a turn table, characterized by a traveling magazine carriage for a supply of record discs adapted to receive a played record disc from the turn table and deposit a succeeding record disc thereon, an actuating motor for said traveling carriage, an electrical energizing circuit for the motor, a make and break device in said circuit controlled by the pick-up arm, a slidable friction rod connecting the make and break device and the pick-up arm and initially adjusting the make and break device through influence of frictional resistance to sliding motion of the connecting rod by its initial movement in either direction and upon further movement of the pick-up arm slidably movable relative thereto against the frictional resistance thereof.

7. A phonographic apparatus wherein a swinging pick-up arm coacts with the record disc upon a turntable characterized by an electric circuit, a make and break device therein including an oscillatory contact member, a complementary contact member engaged by the oscillatory member, a reciprocating actuating rod having sliding frictional engagement with the movable contact member and adapted upon its initial movement in either direction to correspondingly oscillate the movable member by the frictional resistance to its sliding movement and movable relative thereto against the influence of the frictional resistance during further movement of the rod in the same direction, and means for transmitting reciprocating motion to the rod.

8. A phonographic apparatus wherein a swinging pick-up arm coacts with the record disc upon a turntable characterized by an electric circuit, a make and break control device therefor including two relatively movable contact members either of which is movable independently of the other into and out of circuit closing relation therewith, a reciprocating actuating member having operative relation with both movable contact members and by its motion in one direction actuating one contact member into circuit closing

- relation and by its motion in the reverse direction actuating the other contact member into circuit closing relation and means for transmitting reciprocatory motion to the rod.
5. 9. A phonographic record changing apparatus wherein a succession of disc records are to be successively deposited upon and removed from a phonograph turn table characterized by an actuating motor for the turntable, a manually controlled electrical energizing circuit for the turntable motor, a traveling magazine carriage movable to and fro into and out of overlying relation with the phonograph turn table, record disc removing and depositing means associated therewith the depositing means including oppositely disposed ledges from which the record is dislodged for deposit on the turn table in response to the combined fore and aft movement of the magazine carriage, an actuating motor therefor, an electrical energizing circuit for the record changing means motor, a manually operated circuit closer and an automatically operated circuit closer either of which will set the latter motor in operation to actuate the apparatus through a single cycle of operation, means for automatically opening the circuit at the end of a single cycle of operation initiated by either circuit closer the respective motor circuits being controlled independently of each other.
30. 10. A phonographic record changing apparatus wherein a succession of disc records are to be successively deposited upon and removed from a phonograph turn table characterized by an actuating motor for the turntable, a manually controlled electrical energizing circuit for the turntable motor, a traveling magazine carriage movable to and fro into and out of overlying relation with the phonograph turn table, record disc removing and depositing means associated therewith, the depositing means including oppositely disposed ledges from which a record is dislodged for deposit on the turntable in response to the combined fore and aft movement of the magazine carriage, an actuating motor therefor, an electrical energizing circuit for the motor, two independently operated circuit closers in said circuit, one of said circuit closers being automatically actuated by the movement of the pick-up arm to set the motor in operation to effect an exchange of records at the completion of a playing period, and means actuated by the manual operation of the second circuit closer for effecting repetition of the record exchange operation without playing operation of the deposited record, the turn table motor circuit and the record changing means motor circuit being independently controlled.
11. In a phonographic apparatus, the combination with a phonographic turn table, an actuating motor therefor, a traveling record magazine carriage, an actuating motor for shifting the magazine carriage into and out of record changing relation with the turn table, an electric circuit for energizing each motor, a circuit breaker in the phonographic motor circuit, a second circuit breaker in the magazine carriage motor circuit, a control member for the circuit breakers movable through successive steps first in one direction and then in the other, manual means for effecting step by step movement of the control member in one direction by the initial movement of which the circuit closer pertaining to the magazine carriage motor is opened and the circuit breaker pertaining to the turn table motor is closed, means independently of said circuit breaker for closing the magazine carriage motor circuit at the completion of a record playing operation, means actuated by the magazine carriage motor for retracting the control member, the final movement of which operates to open the turn table motor circuit breaker and close the magazine carriage motor circuit breaker, preparatory to another cycle of operations.
12. In a phonographic apparatus, the combination with a phonographic turn table, an actuating motor therefor and an energizing circuit for said turn table motor, including a circuit breaker, of a record changer apparatus, an actuating motor therefor, an energizing circuit for said changing apparatus motor, including a manually operable circuit closer and automatically operable circuit closer means in the changing apparatus motor circuit, manually controlled means for closing the turn table motor circuit breaker and simultaneously opening the changing apparatus motor circuit to prevent actuation of the record changing apparatus during operation of the phonographic turn table, means for closing the changing apparatus motor circuit at the end of the period of operation of the turn table, and means actuated by the changing apparatus motor effective to open the turn table motor circuit and to restore the changing apparatus motor circuit to manual control preparatory to the next cycle of operations.
13. In a phonographic apparatus, the combination with a phonographic turn table, an actuating motor therefor and an energizing circuit for said turn table motor including a circuit breaker, of a record changing apparatus, an actuating motor therefor, an energizing circuit for said changing apparatus motor, a control member manually actuatable in one direction through a step by step motion and means for retracting the control member through reverse step by step motion under influence of the record changing apparatus motor, alternating circuit breakers in the turn table motor circuit and the changing apparatus circuit operated to close the turn table motor circuit and open the changing apparatus motor circuit upon the initial movement of the control member from unoperated position and to open the turn table motor circuit and close the changing apparatus motor circuit upon its final retractive movement into normal position.
14. In a phonographic apparatus, the combination with a phonographic turn table, an actuating motor therefor and an energizing circuit for said turn table motor including a circuit breaker, of a record changing apparatus, an actuating motor therefor, an energizing circuit for said changing apparatus motor, manual means for closing the changing apparatus motor circuit at will independently of the closing of the turn table motor circuit to effect repetitious operation of the record changing apparatus, means operative upon the closing of the turn table motor circuit rendering the manual changing apparatus circuit closing means ineffective and thereby preventing manual closing of the changing apparatus motor circuit during operation of the turn table motor, and means restoring the changing apparatus motor circuit to manual control at the completion of the period of operation of the turn table motor.
15. In a phonographic apparatus, the combination with a phonographic turn table, an actuating motor therefor and an energizing circuit for the turn table motor, of a record changing apparatus, an actuating motor therefor and an

- energizing circuit for the changing apparatus motor, alternately opened and closed circuit breakers in the respective circuits, a common control member therefor operable at the will of 5 the operator for closing the turn table motor circuit and opening the changing apparatus motor circuit to prevent the operation of the record changing apparatus while the turn table is in operation, means for closing the changing apparatus motor circuit at the completion of the period of motor operation of the turn table, means actuated by the changing apparatus motor for restoring the common control member, and thereby reversing the circuit breakers to open the turn 10 table motor circuit and close the changing apparatus motor circuit preparatory to the next cycle of operation, and manual means for closing the changing apparatus motor circuit in initiating operation of the record changing apparatus 15 independently of the operation of said common control member.

16. In a phonographic apparatus, the combination with a phonographic turn table, an actuating motor therefor and an energizing circuit for the turn table motor, of a record changing apparatus, an actuating motor therefor and an energizing circuit for the changing apparatus motor, a reciprocatory rack bar, an escapement mechanism under control of the operator for 20 controlling movement of the bar through a step by step motion, actuating means operated by the changing apparatus motor for restoring the rack bar through a step by step motion, alternately opened and closed circuit breakers in the respective 25 motor circuits alternated by the reciprocatory movements of the rack bar.

17. In a phonographic apparatus, the combination with a phonographic turn table, an actuating motor therefor and an energizing circuit for the turn table motor, a record changing apparatus, an actuating motor therefor and an energizing circuit for the changing apparatus motor, alternately opened and closed circuit 30

breakers in the respective circuits, a normally open circuit closer in the changing apparatus motor circuit, manually operable electro-magnetic means for effecting the closure of such circuit closer to set in operation the changing apparatus motor, and means operated by the motor for automatically opening said circuit closer at the end of the cycle of operation of the record changing apparatus. 5

18. In a phonographic apparatus, a motor driven turn table, a motor actuated record changing apparatus, independently operable motors for the turn table and the record changing apparatus, electrical control circuits for the respective motors, independently operable manual circuit closers in the respective circuits operable to repetitiously close the record changing apparatus motor circuit, an automatically operated circuit closer in the control circuit for the record changing apparatus motor closed at the completion of a playing period for effecting automatic change of record, and means effective to prevent closing of the record changing apparatus motor circuit during the playing period initiated by the closing of the turn table motor circuit. 10 15

19. A phonographic apparatus wherein a swinging pick-up arm coacts with a record disc upon a turntable, characterized by a record changing mechanism, including an actuating motor, an electrical control circuit for the motor, a circuit breaker in said circuit, a traveling pick-up device, a reciprocatory rod actuated by the traveling pick-up and having frictional sliding engagement with the circuit breaker so arranged that the rod may continue to travel with the pick-up in one direction while holding the circuit breaker open, and adapted upon reversal of direction of movement to permit closure of the circuit breaker to set the record changing mechanism in operation and to maintain the circuit breaker closed while said rod continues to move in said reverse direction relative thereto. 20 25 30 35 40

BENJAMIN L. CARTMELL.
